UNITED STATES PATENT OFFICE.

JOHN LAIDLAW, OF GLASGOW, COUNTY OF LANARK, SCOTLAND.

CENTRIFUGAL MACHINE.

SPECIFICATION forming part of Letters Patent No. 319,493, dated June 9, 1885.

Application filed April 29, 1885. (No model.)

To all whom it may concern:

Be it known that I, JOHN LAIDLAW, of the firm of Watson, Laidlaw & Co., of 98 Dundas Street, Kingston, Glasgow, in the counties of Lanark and Renfrew, North Britain, engineer, have invented Improvements in Centrifugal Machines, otherwise known as "hydro-extractors," of which the following is a specification.

This invention relates to improvements in centrifugal machines, otherwise known as "hydro-extractors," and has for its object to provide a revolving bearing for such centrifugal machines or hydro-extractors whereby the friction encountered in driving such machines is considerably less than the friction encountered by the bearings hitherto used for the purpose.

In applying these improvements to that class of centrifugal machines or hydro-extractors in which the basket is carried upon a hollow vertical shaft which is supported upon and is rotated around a suspended stationary shaft there is arranged one set or tier, or two or more such sets or tiers, of rollers of truncated conical form between correspondingly-coned rings or washers, the whole being situated around the inner stationary shaft and within the outer rotating shaft. For a bearing for supporting a vertical rotating shaft at its lower extremity the rollers, which may be in one, two, or more tiers, are arranged around a short vertical shaft or plug, and the whole of the bearing-surfaces within an oil-containing vessel.

Figure 1 is in part an elevation and in part a vertical section of portion of an elastically-suspended centrifugal machine or hydro-extractor, showing the application thereto of a bearing constructed according to and constituting this present invention. Figs. 2 and 3 are respectively a vertical and a horizontal or transverse section through the said bearing, and represented at these figures upon an enlarged scale. Fig. 4 is a vertical section through this improved bearing as applied to a centrifugal machine, the rotating shaft of which is supported from below.

In constructing a bearing according to this present invention for a vertically-suspended rotating tubular shaft such as is represented at *a*, Figs. 1, 2, and 3 of the annexed drawings, the conical rollers *b* are arranged with their axes, and consequently their peripheries, upon lines

radiating to a point in the axis of the stationary shaft *c*. Each of these rollers *b*, as shown, presents a truncated conical appearance, and the inner and outer extremities are spherical. The rollers *b* are arranged around the shaft *c* in such number, and they are of such proportions, that their peripheries are preferably contiguous, or as nearly so as is practicable. When two sets or tiers of rollers *b* are used, as represented at Fig. 2 of the annexed drawings, the said tiers of rollers rotate between the rings *d* and *l* and *e* and *l*, respectively, the bearing-surfaces of these rings being in planes radiating from the points to which the axes of the respective tiers of rollers radiate. The outer faces of the rings *d* and *e* are made convex, and with these convex faces the opposing concave faces of the gun-metal or equivalent collars *f* engage. To the outer rounded extremities of the rollers *b* the annular convex surfaces of the rings *g* are presented. The lower of the two collars *f* is supported upon the nut *h*, which is screwed upon the stationary shaft *c*, while the upper of these collars *f* directly supports the gun-metal or equivalent bush *i*. This bush *i* is secured to the rotating shaft *a* by means of the pin *j*, which is passed tangentially therethrough. The lock-nut *k* is screwed upon the shaft *c*, in order to prevent the nut *h* from coming off or otherwise shifting by vibration.

The bearing hereinbefore described has been mentioned as having two sets or tiers of rollers *b*; but it is to be understood that one, or three, or more such sets or tiers may be used.

At Fig. 4 of the annexed drawings there is represented a bearing having one set or tier of rollers *b* as applied to that class of centrifugal machines or hydro-extractors in which the baskets are carried upon vertical shafts supported at their lower extremities. In this form of bearing where one set or tier of rollers *b* is used the said rollers and rings *d*, *e*, and *g* are arranged in the manner hereinbefore described with reference to Figs. 1, 2, and 3 of the annexed drawings. The collars *m*, Fig. 4, have each a hole formed at its center, which holes admit the lower one of the short shaft or plug *n*, and the upper one of the pin or plug *o* passing therethrough. The short shaft or plug *n* serves to maintain the lower collar *m* and the rings *d* and *e* in their central position, while

the pin or plug *o*, which is formed upon the lower extremity of the rotating shaft *p*, serves to maintain the upper collar *m* in position. The shaft *p* is guided in the tube *q*, the inter- 5 nal diameter of whose lower extremity is pref- erably reduced, as represented at Fig. 4, so as to embrace the rollers *b* and their directly- connected parts. The cap *r* is preferably pro- vided with the lugs *s*, whereby the said cap *r* 10 is screwed tightly upon the tube *q*, and there- by constitutes a closed vessel for containing the oil necessary for lubricating the rolling or friction surfaces of the bearing, the holes *t* and channels *u* being respectively provided for the 15 passage and circulation of the oil to such sur- faces.

I claim—

The improvements in centrifugal machines or hydro-extractors wherein the bearings are constructed of one or more annular sets or tiers 20 of truncated conical rollers and rings, all op- erating substantially as hereinbefore described and shown on the annexed drawings.

In testimony whereof I have signed my name to this specification in the presence of two sub- 25 scribing witnesses.

JOHN LAIDLAW.
